SPOOL OR REEL

Robert V. Olson, Attleboro, Mass., assignor to
Mossberg Pressed Steel Corporation, a corpora-
tion of Massachusetts

Application July 26, 1940, Serial No. 347,609

3 Claims. (Cl. 242—123)

This invention relates to a spool or reel of the type formed of sheet stock and is a continuation in part of my copending application, Serial No. 190,894, filed February 17, 1938, now Patent No. 2,258,580.

The invention has for one of its objects to provide a spool or reel which will have unusually strong heads so that when copper wire is reeled upon the spool and heated for annealing, whereby there is provided considerable expansion because of the greater coefficient of expansion of the copper than the steel of the spool, the strains exerted will be resisted and the heads will maintain their shape in planes at right angles to the axis of the barrel.

Another object of the invention is the provision of a structure which will so support the stresses as to remain concentric whereby to permit of high speed drawing without wobbling or chattering of the spool on its supports.

Another object of the invention is to prevent the entry of wire into the seam between the barrel and the flange of the head which contacts the end of the barrel.

Another object of the invention is to so relate the head and the barrel that, even though there be movement of the head relative to the barrel in a direction axially of the barrel, still no seam will be opened up into which wire may enter.

With these and other objects in view, the invention consists of certain novel features of construction, as will be more fully described, and particularly pointed out in the appended claims.

In the accompanying drawings:

Fig. 1 is a sectional view of a spool embodying this invention;

Fig. 2 is an exploded view of the several parts which go to connect the head to the spool;

Fig. 3 is an end view of the spool;

Fig. 4 is a modification of the invention illustrating the spool without the center core;

Fig. 5 is a sectional view illustrating a still different modification of the invention;

Fig. 6 is a sectional view illustrating a different manner of welding certain of the parts in 45 position.

It is found in the use of spools such as are used in annealing copper wire that when the loaded spool is heated the expansion of the copper wire being greater than the expansion of the steel of the spool causes tremendous stresses to be exerted on the heads of the spool and often a warping of the heads of the spool or some movement of the head axially along the barrel. Such axial movement in some cases may cause an opening

of the joint so that wire on the spool may enter the same; and in order that the wire may be drawn at high speeds it is essential that the spool be accurate and concentric with the center hole or central support. Also, to prevent the entrance of wire into crevices I have so arranged that even though there be a movement of the head relative to the barrel, no such crevices will be opened up. And I have so constructed the spool 10 that the strains may be resisted to prevent the spool from becoming eccentric or any parts from moving beyond the tolerance allowed for high speed production; and the following is a more detailed description of the present embodiment of this invention, illustrating the preferred means by which these advantageous results may be accomplished.

With reference to the drawings, 10 designates the barrel of the spool and 11 the heads of the spool which are formed from sheet stock as shown more fully in Fig. 2. There is a center hole 12 in the head 11 of a size substantially the size of the outer diameter of the barrel 10 so that the barrel 10 will extend into the hole 12 and through the head substantially the thickness of the stock of the head 11 so that the end 13 of the barrel will lie substantially flush with the outer surface 14 of the head 11.

The head and barrel are secured in this relative position by a reinforcing plate 15 having a sleeve 16 extending inwardly therefrom and of a diameter to closely fit the inner surface 17 of the barrel, while the plate 15 engages the outer surface 14 of the head 11. Thus, there is formed about the juncture or seam of the head 11 and the barrel 10 an L-shaped reinforcing member which when secured to the head and the barrel serves to maintain these two in this relative position.

The sleeve 16 may terminate as shown in Fig. 4, or it may extend radially inwardly as at 18 to the center tube 19 and thence outwardly as at 20 along the center tube to be engaged at its end by the rolling outwardly and backwardly of the end 22 of the center tube as illustrated in Fig. 5; or the sleeve may extend radially inwardly as at 24, as shown in Figs. 1 and 2, thence axially outwardly as at 25, again radially inwardly as at 26 and then turning inwardly, again axially as at 27 to engage the abutment 28 raised at intervals from the stock of the tube 19 for such abutting relation, while the thinned edge of this tube 19 may be rolled outwardly about the curved surface 30 of the portions 27 as at 31 to lock this reinforcing member centrally in

position. The outer surface 32 of this portion 26 is in substantially the same plane as a tangent 33 to the rolled edge 34 at the periphery of the head so that the spool may be set upright upon its end and may rest upon the surface 32 and edge 33 for better supporting of these spools in this position, such, for instance, as stacking a series of spools one on top of the other endwise.

In order to secure the reinforcing member to the barrel and head, I will weld the same to 10 the barrel through the sleeve portion 16 as indicated at 35 and then will weld the plate 15 of the reinforcing member to the head by a suitable weld as at 36.

The weld 35 may take the form of a continuous 15 resistance weld as shown in Figs. 1, 4, and 5, or the form of a series of spot welds as shown in Fig. 6 as at 37; while the weld at 36 securing the plate 15 to the head 11 may be in the form of a continuous resistance weld or preferably in 20 the form of spot welds in staggered relation about two different radii from the center axis as illustrated in Fig. 3.

The foregoing description is directed solely towards the construction illustrated, but I desire 25 it to be understood that I reserve the privilege of resorting to all the mechanical changes to which the device is susceptible.

I claim:

1. In a reel or spool of sheet metal a head 30 having a central opening therein of approximately the size of the outer diameter of the barrel and with the surface defining said opening relatively smooth and unbroken, a barrel extending into said opening, a central tube, an 35 end plate abutting the outer surface of said head and having a flange extending into the opening

in said barrel along said barrel and then extending radially inwardly, then outwardly axially of the barrel, then radially inwardly to engage said tube, and a weld located between said flange and barrel to hold said head and barrel in assembled relation.

2. In a reel or spool of sheet metal a head having a central opening therein of approximately the size of the outer diameter of the barrel and with the surface defining said opening relatively smooth and unbroken, a barrel extending into said opening, a central tube, an end plate abutting the outer surface of said head and having a flange extending into the opening in said barrel along said barrel and then extending radially inwardly, then outwardly axially of the barrel, then radially inwardly to engage said tube, a weld located between said flange and barrel, and a weld located between said plate and head to hold said head and barrel in assembled relation.

3. In a reel or spool of sheet metal having a head at each end thereof, each head having a central opening therein approximately the size of the outer diameter of the barrel and with the edge of the opening smooth and unbroken, a barrel having continuous surfaces at the end portions thereof extending into said openings, and plates abutting the outer surfaces of said heads and each plate having a continuous unbroken circular flange extending into the opening of the barrel, the free ends of said flanges being spaced from each other and a weld located between each of said flanges and the barrel and about the periphery of the barrel to hold said heads and barrel in assembled relation.

ROBERT V. OLSON.
